UNITED STATES PATENT OFFICE.

FRANK SNYDER, OF SYRACUSE, NEW YORK.

INTERNAL-COMBUSTION ENGINE.

1,174,632.

Specification of Letters Patent. Patented Mar. 7, 1916.

Application filed November 16, 1914. Serial No. 872,388.

To all whom it may concern:

Be it known that I, FRANK SNYDER, a citizen of the United States, and resident of Syracuse, in the county of Onondaga, in the

5 State of New York, have invented new and useful Improvements in Internal-Combustion Engines, of which the following, taken in connection with the accompanying drawings, is a full, clear, and exact description.

10 This invention relates to certain improvements in internal combustion engines of the rotary piston type in which the bore of the cylinder and piston revolving therein are cylindrical and co-axial, except that the piston is provided with peripheral pockets registering successively with the fuel inlet and exhaust ports and coöperating with a suitable plunger which serves to compress the fuel admitted to said pockets when registered 15 with the fuel inlet, preparatory to ignition immediately following the register of the pockets with the plunger, or while the plunger is still in its compressing position in either of the pockets.

20 The main object is to produce a simple, compact and highly efficient engine of this type at a comparatively low cost by utilizing the piston to control the fuel inlet and exhaust ports, and thereby obviating the use 25 of valves, and also by utilizing the pockets in the piston as portions of the compression chamber in which the explosive mixture is compressed and ignited while under compression, thereby utilizing the expansive 30 force of the ignited mixture directly against the heads of the piston formed by said pockets to effect a continuous rotation of the piston in the same direction.

Another object is to utilize the plunger 35 for the double purpose of compressing the explosive mixture in the pockets of the piston and opposing the expansive force of the ignited mixture between said plunger and either head of the rotary piston.

40 A further object is to synchronize the movement of the plunger with that of the piston, so as to cause it to positively enter and leave the pockets successively at the proper time to effect the desired compression 45 of the explosive mixture and oppose the expansive force of the same when ignited, whereby such force will be applied directly to the heads, of the rotary piston for impelling the same in the same direction.

Other objects and uses relating to specific 55 parts of the engine will be brought out in the following description.

In the drawings, Figures 1 and 2 are, respectively, a top plan and a side elevation of a rotary internal combustion engine, embodying the various features of my invention. Fig. 3 is an end view of the same engine showing more particularly the cam operated lever for operating the plunger, the cam being omitted. Fig. 4 is an enlarged 60 transverse vertical sectional view taken on line 4—4, Fig. 2. Fig. 5 is an enlarged longitudinal vertical sectional view taken on line 5—5, Fig. 1. Fig. 6 is an enlarged longitudinal vertical sectional view through the 65 upper portion of the engine taken on line 6—6, Fig. 1, showing particularly the plunger and its operating means. Fig. 7 is a face view on a reduced scale of the piston shown in Figs. 4 and 5. Fig. 8 is a detail sectional 70 view of the roller-end of the plunger operating lever which engages the cam. Figs. 9, 10 and 11 are detail sectional views similar to Fig. 4, showing the rotary piston and plunger in three different positions, viz; the 75 firing position; that in which one of the pockets begins to exhaust the spent gases and the other pocket is taking in a fresh charge of the explosive mixture; and that in which the plunger is beginning to compress such charge in one of the pockets.

As illustrated, this engine comprises a stationary cylinder, —1—, having a cylindrical bore —2—, a valveless fuel inlet port —3— and a valveless exhaust port —4—, 80 said cylinder being provided with removable end heads —5— which are secured to the adjacent ends of the main body by bolts —6— and are provided with central co-axial bearings —7— for receiving and supporting a 85 shaft —8—, carrying a cylindrical piston —9—, and a cam wheel —10— which also serves as a balance-wheel.

The cylinder —1— is preferably made of 90 cast metal and may be of any desired length or diameter and is provided with an integral hollow casing —12— projecting laterally (in this instance upwardly) therefrom at one side of its axis to form a tangential compression chamber —13— in which is movable a fuel-compressing plunger or reciprocating piston —14— hereinafter more fully described, said compression chamber com-

municating with the bore —2— of the cylinder between the inlet port —3— and exhaust port —4— in the direction of movement of the rotary piston —9—.

- 5 The rotary piston —9— is of substantially the same diameter and length as the interior bore of the cylinder so as to establish a close running joint therewith, and is provided near its ends with annular grooves for receiving packing rings —15— to further prevent leakage of the gases which may be introduced into the cylinder between said ends.

10 The rotary piston —9— is provided with diametrically opposite eccentric surfaces depressed to form peripheral pockets —16— and is also provided with circumferentially extending concentric surfaces, which carry the packing rings —15— and terminate at their advance ends in abrupt substantial radial abutments —17— which are diametrically opposite and constitute piston heads against which the expanded gases impinge to impel the piston rotarily in one direction, the radial depth of the remaining portions 15 of each pocket being gradually diminished circumferentially from the heads —17— until the eccentric surfaces merge with the concentric peripheral portions of the piston. The circumferential length of the inner end 20 of the compression chamber approximates one-fourth of the circumference of the bore of the cylinder, while the concentric surfaces of the rotary piston approximate in length that of the inner end of the compression 25 chamber, and the circumferential lengths of the eccentric surfaces is slightly greater than that of the concentric surfaces so as to produce with a portion of the bore an ignition chamber for the spark plug just in advance 30 of the compression chamber, or between said compression chamber and exhaust port.

35 The distance between the inlet port and farther side of the compression chamber is greater than the length of the eccentric surface of the rotary piston so that the inlet will be cut off by the piston before the advance ends of the fuel-receiving pockets are registered with the ignition chamber or spark plug, although it is to be understood 40 that the pocket serves as a means of connection between the inlet and compression chamber as soon as the advance end of each pocket leaves the inlet and until the following concentric portion of the rotary piston 45 closes the inlet. It will also be observed that the distance between the compression chamber and exhaust is less than the circumferential length of the eccentric surfaces of the rotary piston, thus permitting the spent 50 gases to exhaust on one side of the piston, while the explosive mixture is being drawn in at the opposite side, communication between the inlet and exhaust being cut off by the concentric portions of said piston. The 55 concentric portions of the periphery of the

rotary piston are also provided with lengthwise grooves extending between the innermost packing rings —15— for receiving additional packing strips —15'— and further prevent leakage of the gases around said 70 piston.

75 The compression chamber —13— and plunger —14— are preferably rectangular in cross section to prevent turning of the plunger which latter is provided with a convex inner face —18— conforming as nearly as possible to the curvature of the bottom of the pockets —16— and concentric portions of the periphery of the piston, so as to fit closely to the bases of the pockets when the 80 plunger is at the limit of its inner movement for effecting the maximum degree of compression of the explosive mixture previously admitted to the pocket into which the plunger may be forced, as shown more 85 clearly in Figs. 4 and 9.

90 The perimeter of the plunger —14— is provided with one or more grooves for receiving packing rings —20— to prevent leakage of the gases around said plunger which is adapted to fit closely within the compression chamber to further avoid such leakage. This plunger is reciprocated in synchronism with the movement of the rotary piston in such manner as to cause it to 95 enter the pockets —16— as they are successively registered therewith, and for this purpose is connected by pitmen —21— to crank-arms —22— on a rock-shaft —23— which is journaled in suitable bearings in 100 the upper portion of one side of the casing —12— and is provided with a relatively long operating lever —24— external to the casing and cylinder and having its free end provided with a roller bearing —25— riding 105 in a cam groove —26— in the adjacent side of the cam wheel —10—. This cam groove is continuous, but is composed in this instance of two similar parts, one for each of the pockets —16— and each adapted to effect a complete reciprocal operation of the plunger —14—, so as to cause said plunger to enter each pocket as it is registered with the compression chamber after receiving a 110 charge of the explosive mixture by its previous registration with the fuel inlet —3—. It, therefore, follows that the plunger completes two cycles of movement during each revolution of the piston and that immediately upon the movement of each piston 115 head —17— past the compression chamber, the plunger is caused to descend quickly by the particular form of the cam operating the same to compress the previously admitted charge of the explosive mixture in 120 that particular pocket into a comparatively small space between what may be termed the front face of the plunger and piston head —17—, as indicated in Figs. 4 and 9, at 125 which space is located a spark plug —27— 130

adapted to be connected to any suitable source of electric energy to ignite the compressed gases at about the same time that the plunger reaches the limit of its inward 5 stroke, it being understood that the ignition may be regulated by any suitable timing device not necessary to herein illustrate or describe.

The operation is as follows, assuming that 10 the plunger —14— is in its extreme inner position in approximate contact with the base of one of the pockets —16— for compressing the previously admitted explosive mixture into the relatively small space between 15 the head of said pocket and adjacent side of the plunger, as shown in Fig. 4, and that the compressed gases have just been ignited. It then follows that the expansive force of the gases upon the adjacent head 20 —17— of the piston will rotate said piston in the direction indicated by arrow —X—, by reason of the fact that the plunger —14— then resists such expansive force and causes it to act in one direction only away from the plunger or against the adjacent head 25 —17— of the piston —9—. As the piston head advances away from the plunger toward the exhaust —4—, the space in the pocket between said head and plunger becomes 30 enlarged, thereby gradually diminishing the expansive force which has already performed its work by the time the head —17— reaches said exhaust port to exhaust the spent gases, thus allowing the plunger 35 to be raised slowly, but still maintaining relatively close contact between the base of the pocket and face of the plunger. During this initial operation of the piston, the opposite piston head —17— will have moved across the inlet —3— to register the corresponding pocket —16— with said inlet, the movement of the head across the inlet serving to create a partial vacuum to draw in a fresh charge of the explosive mixture 40 which is carried toward the inner end of the plunger chamber —13—, and as soon as communication is established between the advance end of the pocket which has just moved across the inlet and plunger chamber, 45 the plunger —14— is caused to move outwardly with increased speed to accelerate the entrance of the explosive mixture between the base of that pocket and the adjacent face of the plunger until the rotary piston assumes approximately the position 50 shown in Fig. 11, whereupon the plunger begins to descend with such speed as to enter such pocket at about the same time the corresponding piston head —17— passes out from under the plunger, whereupon the continued movement of the plunger into the pocket produces a high degree of compression of the explosive mixture therein by the time the corresponding piston head has 55 passed the spark terminals of the plug

—27—, at which time a spark is produced to ignite the compressed gases to repeat the operation previously described.

Although I have shown a specific means for operating the plunger in synchronism with the rotary piston, it is evident that any other suitable means may be substituted therefor without departing from the spirit of this invention, and it is also evident that the number of pockets in the piston may be varied and that the piston may be extended lengthwise and provided with additional sets of pockets operating in conjunction with corresponding plungers, all of which changes are comprehended in this application, and therefore, I do not limit myself to the precise construction shown and described.

What I claim is:

1. In a rotary internal combustion engine, the combination of a cylinder having a circular bore and a compression chamber tangential thereto, said cylinder having a valveless inlet port and an exhaust port, a rotary piston movable in said bore and having a concentric surface of substantially the same radius as that of the bore, and a depressed eccentric surface, a reciprocating piston movable in the compression chamber and co-operating with the eccentric surface to compress the fuel, and means for synchronizing the movement of the reciprocating piston with that of the rotary piston.

2. In a rotary internal combustion engine, the combination of a cylinder having a circular bore and a compression chamber tangential thereto, said cylinder having a valveless inlet port and an exhaust port, a rotary piston movable in said bore and having diametrically opposite concentric surfaces and opposite intervening eccentric surfaces, a reciprocating piston movable in the compression chamber and co-operating with the eccentric surfaces to compress the fuel, and means for synchronizing the movement of the reciprocating piston with that of the rotary piston.

3. In a rotary internal combustion engine, the combination of a cylinder having a circular bore and a compression chamber extending from a plane tangential to one side of the bore to a plane near that of a radial line drawn through the center of the bore parallel with the tangential side, said cylinder having an inlet port and an exhaust port, a rotary piston having portions of its surface concentric and approximating in length the corresponding length of the inner end of the compression chamber and eccentric portions of greater length than the concentric portions, a reciprocating piston movable in the compression chamber, and means for synchronizing the movement of the reciprocating piston with that of the rotary piston.

4. In a rotary internal combustion engine,

the combination of a cylinder having a circular bore and a compression chamber extending from one side around approximately one-fourth of the circumference of the bore,
5 said cylinder having a valveless intake and a valveless exhaust, a rotary piston controlling the intake and exhaust and having diametrically opposite concentric surfaces and diametrically opposite eccentric surfaces,
10 said eccentric surfaces being of less circumferential length than the distance between the intake and radial side of the compression chamber and of greater circumferential length than the distance between the radial
15 side of the compression chamber and ex-

haust, a reciprocating piston movable in the compression chamber and having its inner face curved to conform to the eccentric faces of the rotary piston and gradually increasing in length from the radial side of the compression chamber to the tangential side thereof, and means for synchronizing the movement of the reciprocating piston with that of the rotary piston. 20

In witness whereof I have hereunto set 25
my hand this 3d day of November 1914.

FRANK SNYDER.
